MECHANICAL PENCIL

Frank P. Cooper, Clifton, Ohio

Application November 26, 1937, Serial No. 176,592

6 Claims. (Cl. 120—17)

This invention relates to mechanical pencils and has for an object to provide an improved construction which is comparatively simple and which will always function to feed a lead outwardly and retract lead inwardly a desired distance as long as the supply of leads lasts.

Another object of the invention is to provide a mechanical lead pencil wherein a magazine is adapted to feed new leads to a suitable lead-holding-and-ejecting structure from time to time as the respective leads are used.

Another object of the invention is to provide a mechanical lead pencil wherein substantially all of the moving parts are arranged in the ferrule of the pencil.

An additional and more specific object of the invention is to provide a mechanical lead pencil wherein gripping means are actuated by the rotating barrel in such a way that the gripping means are caused to grip and then move forwardly a lead as the same is needed.

In the accompanying drawings—

Figure 1 is a longitudinal vertical sectional view through a mechanical lead pencil disclosing an embodiment of the invention;

Figure 2 is a sectional view through Figure 1 approximately on the line 2—2;

Figure 3 is a transverse sectional view through Figure 1 on the line 3—3;

Figure 4 is a transverse sectional view through Figure 1 approximately on the line 4—4;

Figure 5 is a transverse sectional view through Figure 1 approximately on the line 5—5;

Figure 6 is a transverse sectional view through Figure 1 approximately on the line 6—6;

Figure 7 is a view similar to Figure 1 but showing most of the mechanism in elevation;

Figure 8 is a sectional view through Figure 7 approximately on the line 8—8;

Figure 9 is a perspective view of a hollow piston disclosing certain features of the invention;

Figure 10 is a perspective view of a gripper embodying certain features of the invention;

Figure 11 is a side view partly broken away of the structure shown in Figure 10;

Figure 12 is a side view of a casing member embodying certain features of the invention;

Figure 13 is a top plan view of the structure shown in Figure 12; and

Figure 14 is a perspective view of an anchor disclosing certain features of the invention.

Referring to the accompanying drawings by numeral, 1 indicates a hollow barrel formed of any desired material, as, for instance, metal, wood, "Bakelite", or other suitable composition.

This barrel at the upper end is provided with a restricted portion 2 for receiving a cap 3. It will be understood that the upper end may be formed in various ways and may be provided with a rubber eraser without departing from the spirit of the invention. The lower end of the barrel is provided with an annular groove 4 and lugs 5 which may be integral with the barrel or rigidly secured thereto in any desired manner. The exterior surface of the lower end of the barrel 10 tapers at 6 so as to line up with the taper of a cone-shaped ferrule 7. This ferrule has a cylindrical part 8 fitting into the lower end of the barrel 1 so that an exterior bead 9 may fit into the groove 4 in order to rotatably secure the ferrule to the barrel. The cylindrical part 8 is preferably formed with one or more notches 10 so that the upper end may be sprung inwardly in order that the bead 9 may be slipped into position and held therein by the resiliency of the material, 20 which may be metal, rubber, or the like.

From the description of the ferrule 7 and barrel 1 it will be seen that these members are rotatable in respect to each other, and ordinarily when a lead is adjusted the ferrule 7 is held stationary 25 and the barrel 1 rotated though the reverse action could take place without changing the construction. The hollow part or chamber 11 is adapted to receive one or more extra leads 12 while the lead 12' is in use. In order to separate 30 the leads in the chamber 11 from the interior of the ferrule 7 and to cause the proper feeding action from the chamber 11 to the interior of the ferrule 7, there is provided a disk 13 of metal, rubber, or other suitable material. This disk is 35 provided with notches 14 adapted to receive the lugs 5. These parts fit rather snugly so that in effect the barrel 1, disk 13, and associated parts function as a single integral member.

It will also be noted that the disk 13 is provided with an integral depending tubular extension 15 adapted to receive a cam 16 as herein-after more fully described. The disk 13 is provided with an aperture in alignment with the bore of the tubular extension 15 so that the guide tube 45 17 may extend through the disk 13 so as to present a guide for the lead 12'. A scoop 18 is preferably integral with the tube 17, and is provided with a coiled portion formed with a curved arm 19 and an arch-shaped center portion 20 whereby 50 the leads 12 are guided into the arch-shaped center portion 20 and then allowed to slide by gravity into the tube 17. When this is done the pencil is held at an angle of approximately 45° to the horizontal and the ferrule held stationary while 55

the barrel is rotated, or a reverse action could take place. If there are a large number of leads 12 in the chamber 11, only one lead can enter, as clearly indicated in Figure 1. When this lead has been used and a new one is desired, the entire pencil is held at an angle of about 45° and the ferrule is held stationary while the barrel is rotated until a new lead slides down into the ferrule 7 where it may be grasped by the jaws 21 and 22 as hereinafter fully described.

An aligning sleeve 23 fits over the lower end of tube 11 and over the upper end of a lead-guiding tube 24 so that these tubes will be in alignment. The tube 24 extends downwardly to near the outlet end of the ferrule 7 where it is slit or notched at 25 and 26, whereby the lower end may be constricted by the parts being sprung toward each other, and provide friction whereby the lead 12' can not fall out of the pencil. However, the jaws 21 and 22 may force the lead downwardly and overcome the friction produced by the gripping lower end of the guiding tube 24. This tube is provided with notches 27 and 28 so as to permit the jaws 21 and 22 to move into the tube, grip the lead therein, and move the same downwardly a certain distance. The tube 24 is welded or otherwise rigidly secured to a connecting member which may be called an anchor 29. This anchor is shown more in detail in Figure 14, from which it will be observed that there is provided a pair of upstanding arc-shaped side members 30, abutments or stops 31, and anchoring projections 32. These projections extend through suitable apertures in the ferrule 7, as shown in Figure 1, whereby the anchor 29 and all parts connected therewith will function as if they were integral and therefore will rotate with the ferrule. From Figures 1 and 7 it will be seen that the members 30 act to support the sleeve 23 though ordinarily the sleeve is held properly in place by friction.

The gripping jaws are preferably two in number and formed as shown particularly in Figures 10 and 11. From these figures it will be seen that each jaw is provided with a gripping surface 33 formed on the lower end of the gripper lever 34, which is offset at 35 and at the upper end is formed preferably with an integral bearing shaft 36 and arms 37 and 38. The bearing shaft 36 of the respective grippers are rotatably mounted in the openings or apertures 39 of the casing 40. This casing, as shown in Figures 12 and 13, is provided with a lower guiding body 41 which is provided with a pair of resilient tongues 42 adapted to press against the guiding tube 24 and thereby prevent any independent up-and-down motion of the casing. When both the grippers are arranged in position as shown in Figure 2, the respective arms 37 and 38 will extend through openings 43 and 44 of a tubular member which for purposes of identification may be called a hollow piston 45, arm 37 of the right-hand gripper functioning in opening 44 and arm 38 of the left-hand gripper functioning in opening 43. This hollow piston is provided with a notch or opening 46 (Figs. 5 and 9) on diametrically opposite sides so as to present respectively abutments 47 and 48 adapted to strike the abutments or stops 31. The hollow piston 45 extends over the upper part 70 of the casing 40 and is provided with a circular reduced upper end 49 which is slidingly fitted over the cam 16, which cam is rigidly secured to the depending member or sleeve 15 which is held stationary in respect to the barrel 1. The upper end 49 is provided with apertures 51 and 52

(Figs. 4 and 9) adapted to receive the journal ends 53 and 54 of an arc-shaped bar 55. The journal ends or members not only extend through the apertures 51 and 52 but extend into the respective cam grooves 56 of cam 16.

It will be noted from Figure 9 that each of the openings 43 and 44 is provided with an enlarged end 57 and reduced end 58. This structure is presented in order to provide freedom of movement to the arm in the enlarged end while the push and pull is being applied to the arm in the reduced end, so that the jaws 21 and 22 may be swung into engagement with the lead 12' or out of engagement therewith.

In operation it is intended that the barrel be 15 revolved and the ferrule be held stationary, which procedure performs two acts: When the barrel is rotated from right to left or clockwise (as viewed from the upper end) lead is guided into the lead-feeding tube and then propelled outward through the end of ferrule. When the rotation of the barrel is from left to right or counterclockwise, the lead is retracted or drawn back into the pencil. If the opposite procedure is adopted, that is if ferrule is revolved and barrel 25 held stationary, the ferrule would have to be revolved in the opposite direction to accomplish each of the above results and the selective mechanism within the barrel would be inoperative.

Referring to Figure 10, arms 37 are used for 30 propelling lead outward and arms 38 are used for retracting or drawing lead backward into the pencil. These arms are plainly shown in Figure 5. Whichever arms are functioning, that is both 38's or both 37's are within the narrow part of 35 openings 43 and 44 in the piston. The piston has four openings besides the two longitudinal slots. The narrow parts of the openings 43 and 44 in each half of the piston, that is, each half as separated by the two longitudinal slots, face each 40 other with the wider portion facing the longitudinal slots, which construction is such that if the piston is revolved slightly from right to left, arms 37 are within the narrow section and arms 38 are within the wider section and when revolved 45 from left to right arms 38 are within the narrow section and arms 37 are within the wider section. The wider sections of the openings serve two purposes; first, they allow arms within them to swing freely when the push or pull is applied to the 50 arms within the narrow section in propelling the lead outwardly or retracting the lead inwardly, and, second, they prevent gripping arms from swinging in too wide an arc on the inward swing of the grippers when there is no lead in the lead-guiding tube, thus preventing gripping arms 55 from pressing on sides of lead-guiding tube.

The longitudinal slots have each two faces or abutments, that is, there are two 48's and two 47's so that when piston revolved slightly in one direction one set of faces or abutments come in contact with one side of lugs 31 and when revolved in the opposite direction the opposite face of abutments 47 and 48 come in contact with the opposite side of lugs 31. This slight rotary movement of the piston in respect to ferrule 7 in either direction is for the purpose of engaging the proper set of arms of the grippers for propelling the lead outward or for retracting or pulling the lead back within the pencil, the rotary motion of the piston being governed as to direction by the direction of rotation of the barrel imparted to the piston through the cam and journal ends in the grooves of the cam. The arms within the narrow section of the openings in the piston 75

are the ones to which the longitudinal movements of the piston are applied.

When the rotary motion of the piston in respect to ferrule 7 is stopped by abutments 47 or 48 against lugs 31, continued rotary motion of the barrel causes the piston to move back and forth longitudinally. The longitudinal movement of the piston is imparted to the arm of the grippers in the narrow portion of the openings of the piston.

If the longitudinal movement is applied as a push or pull to arms 37, the push swings grippers in against the lead and pushes lead outwardly and the pull swings grippers outwardly away from lead and pulls grippers up to the highest point where the action is again repeated and continues to be repeated as long as barrel is rotated from right to left. When arms 38 are within the narrow section of openings in piston 20 the push or pull applied to these arms through barrel being revolved from left to right, results in the opposite action to these arms, that is, a push on these arms swings grippers outwardly away from lead and downwardly to the lowest point of their longitudinal travel and the pull swings grippers inward against lead and upward to the highest point when the action is again repeated, and continues to be repeated as long as barrel is rotated in the same direction.

The resilient tongues 42 of casing 40 bearing on lead-guiding tube 24 not only prevent any independent upward and downward motion of the casing, but the degree of resistance offered determines the tightness of the grip of the grippers upon the lead. This casing carrying the grippers is moved longitudinally back and forth by the push and pull applied to the arms 37 or the arms 38.

During the first part of the movement of the barrel the arms 37 and 38 will change their respective positions in the respective openings 33 and 34 and thereby cause the jaws 21 and 22 to grip the lead 12'. The continued rotation of the barrel in the same direction will cause the journal members 53 and 54 to act on certain of the cam grooves 56 and move the parts downwardly or toward the outlet opening of the ferrule. The downward or longitudinal movement of the parts takes place while jaws 21 and 22 are gripping the lead. This will cause the lead to protrude beyond the outlet opening of the ferrule. This action may be repeated from time to time as additional parts of the lead are to be exposed for use.

When the lead has been used until the jaws 21 and 22 can not grip the same with the jaws in the upper position, a new lead is guided into the tube 24 and the jaws will grip the lower part of this new lead and move the same downwardly as just described so that the unused part of the previous lead will be pushed outwardly a short distance. In this way practically all the lead in each stick of lead may be completely used.

In feeding a lead forwardly or outwardly if the ferrule 7 is continually rotated in one direction instead of part of the time in one direction and part of the time in the opposite direction, the journal members 53 and 54 will move upwardly to the top or upper end of two of the grooves 56 and will then pass downwardly along the remaining two grooves. The first part of the downward movement will cause a reverse movement of the piston 45 and, consequently, the jaws will be opened instead of closed. By continuing the rotary movement in the same direction the next upward movement of the rotary piston 45 will

cause the jaws to grip and pull the lead 12' back into the ferrule. It will therefore be seen that the lead may be propelled or retracted as desired.

I claim:

1. A mechanical lead pencil comprising a hollow barrel adapted to receive a plurality of leads, a hollow ferrule rotatably secured to one end of said barrel, said ferrule having an outlet opening, means in said barrel for guiding one of said leads at a time into said ferrule, and means including a pair of swinging jaws in the ferrule for intermittently grasping and moving the lead therein to and through said outlet opening, said means being reversible whereby said lead may be withdrawn.

2. A mechanical lead pencil comprising a hollow barrel formed with a magazine adapted to receive a plurality of leads, a hollow ferrule rotatably secured to one end of said barrel, said ferrule having an outlet opening, a lead guiding tube extending from near said magazine to said outlet opening, means in said barrel for automatically moving one lead at a time from the magazine into alignment with said lead guiding tube; said means including a coiled sheet member having an arc-shaped center merging into a tubular guide extending to said lead guiding tube, and means including a pair of swinging jaws in the ferrule for intermittently gripping and moving the lead therein toward and through said outlet opening, said means being reversible to retract said lead to provide a desired protuberance of lead from said ferrule.

3. A mechanical lead pencil comprising a hollow barrel formed with a magazine adapted to receive a plurality of leads, a hollow ferrule rotatably secured to one end of said barrel, said ferrule having an outlet opening, a lead guiding tube extending from near said magazine to said outlet opening; means in said barrel for moving one of said leads at a time from the magazine into alignment with said lead guiding tube, said means including an apertured disk rigidly secured to said barrel and a curved member acting as a scoop for directing lead in the barrel one at a time into said lead-guiding tube, and a pair of swinging gripping jaws in the ferrule for intermittently gripping and feeding the lead in said lead guiding tube toward and through said outlet opening.

4. A mechanical lead pencil comprising a hollow barrel adapted to receive a plurality of leads, a hollow ferrule rotatably secured to one end of said barrel, said ferrule having an outlet opening, means in said barrel for guiding one of said leads at a time into said ferrule, and means in the ferrule for intermittently gripping and moving the lead therein toward said outlet opening, said means including a pair of swinging gripping arms, a member longitudinally reciprocable in respect to said barrel and rotatable in respect to said ferrule; for swinging said arms into and out of functioning position and also for moving said arms longitudinally of the ferrule while in either a functioning or non-functioning position and a cam actuated by said barrel for causing said reciprocable and rotatable member to function.

5. A mechanical lead pencil comprising a barrel, a hollow substantially cone-shaped ferrule having one end formed with a lead outlet and the other end rotatably secured to the barrel, means for guiding a lead from the barrel into the ferrule, a lead tube in the ferrule for preventing accidental movement of a lead through said outlet, a pair of swinging grippers positioned

- to grip a lead and then move the same toward and through said outlet, said gripper comprising a pair of levers pivoted at one end and formed with gripping jaws at the other end, and means for actuating said grippers as said barrel revolves and said ferrule is held stationary, said means including a hollow piston longitudinally recipro-
5 cable in respect to said barrel and rotatable in respect to said ferrule for swinging said jaws into and out of functioning position and after each swinging movement moving the jaws longitudinally of the ferrule, and cam means carried and held so as to act as if integral with the barrel for actuating said hollow piston.
- 10 6. A mechanical lead pencil comprising a barrel, a hollow ferrule rotatably secured to said barrel and formed at the end opposite the barrel with an outlet, a lead-guiding tube for preventing a lead from accidentally passing through said outlet, said tube having a pair of elongated openings in the sides, a pair of swinging grippers formed with gripping jaws adapted to be moved through said openings for gripping a lead in said tube, a casing surrounding said grippers formed with resilient tongues pressing on said lead-guid-
15 ing tube for giving resistance to sliding motion of
- 20 25

the casing in respect to the tube, an anchor se-
cured to said ferrule and extending through said casing for preventing independent rotation of said casing, a pipe extending from said barrel for guiding a lead from said barrel into said lead-
10 guiding tube, a piston recipro-
cable in respect to said barrel and rotatable in respect to said ferrule, said piston being formed with abutments and with a plurality of pairs of circumferentially extending openings larger at one end than at the other, said grippers being swingably mounted on said casing and each gripper being provided with a projection extending through an opening in said piston, there being one projection for each opening in said piston whereby when said ferrule rotates a short distance in one direction said 15
grippers will swing in one direction for gripping a lead in said lead-guiding tube and when rotated a short distance in the opposite direction said grippers will be swung in the opposite direction to a non-functioning position, and cam means secured to said barrel for rotating said piston and moving the same longitudinally of the ferrule on each rotary movement.

FRANK P. COOPER.
